UNITED STATES PATENT OFFICE.

MORRIS B. OKUN, OF CHICAGO, ILLINOIS, ASSIGNOR TO A. MURPHY, OF CHICAGO, ILLINOIS.

SIDE-RAIL STRUCTURE.

1,361,610.

Specification of Letters Patent.

Patented Dec. 7, 1920.

Original application filed May 20, 1918, Serial No. 235,590. Divided and this application filed January 27, 1919. Serial No. 273,295.

To all whom it may concern:

Be it known that I, MORRIS B. OKUN, a citizen of the United States, residing at Chicago, in the county of Cook and State of Illinois, have invented a certain new and useful Improvement in Side-Rail Structures, of which the following is a full, clear, concise, and exact description, reference being had to the accompanying drawings, forming 10 a part of this specification.

My invention relates to side rails for wooden bed structures and has for its object the provision of an improved structure of this type whereby the side rails of 15 the bed may be suitably united to the wooden posts of a bed. The structure contemplates that the rails may be reversibly mounted in position, as this term is understood in the art.

20 This present application is a divisional application of my application Serial #235,590, filed May 20, 1918.

My invention contemplates in its preferred form a side rail structure made of 25 metal which is so constructed that it is entirely sanitary by covering up the slot ordinarily provided in the wooden post. The slot of the corner post is, when not closed, a source of dust and other accumulations 30 which contribute very largely to unsanitary conditions of a bed. With my improved structure one of its advantages consists in the elimination of this unsanitary feature.

35 I will explain my invention more in detail by referring to the accompanying drawing, in which—

Figure 1 is a fragmentary perspective view showing a side rail of a bed as mounted upon the post in accordance with my invention;

Fig. 2 is a similar view showing the side rail in its reversed position;

Fig. 3 is a sectional view on line 3—3 of 45 Fig. 1;

Fig. 4 is a sectional view on line 4—4 of Fig. 3, and

Fig. 5 is a sectional view on line 5—5 of Fig. 4.

50 By referring more particularly to Figs. 1, 2, 3, 4 and 5, I show a fragmentary end portion of a side rail 20 for a bed. This side rail has at its extremity an angular face plate 21 riveted thereto by the rivets

22. This face plate is adapted to abut a 55 corner post 23 of the bed in the illustrations of Figs. 1, 2, 3, 4 and 5, this corner post is designed to be of the customary wooden variety. The post has a recessed portion 24 preferably in the form of a slot 60 across which extends a bolt 25. This bolt or hanger is adapted to coöperate with the reversible finger 26. This finger has a tail piece 27 by which it is riveted to and secured upon the side rail and face plate 65 through the agency of the rivets 22. The finger 26 has recesses 28 adapted to fit the bolt 25.

In the form shown, the finger has flaring inclined sides as shown at 29 leading away 70 from the recessed portions 28, these flaring portions serving to draw the side rail closely against the corner post when the two parts are hooked together as shown in the illustrations. Shoulders 30 are provided for 75 the finger 26 which preferably abut the end face plate 21.

From this description the operation of the structure will be readily apparent. The finger 26 by virtue of its construction draws 80 the side rail and post tightly together and the end face plate 21 maintains the proper rectangular relationship between these parts. The tail piece 27 of the finger 26 projects through a hole provided in the face 85 plate and this also serves to strengthen the connection between the three parts 20, 21 and 27. By reason of the fact that the finger 26 is symmetrically constructed on its opposite sides, the structure is of the reversible 90 type so that the side rail 20 may occupy either the position shown in Fig. 1 or the position shown in Fig. 2.

It will be noted that the plate 21 absolutely closes and seals the opening of the 95 slot 24, thus fulfilling all of the sanitary requirements with regard to structures of this kind.

It must be understood that other similar structures can be used not having the exact 100 arrangements as herein disclosed, but which would still be comprehended within the terms of the claim.

The length of the face plate 21 is such that it aids materially in holding all of the 105 various parts in alinement.

From what has been described the nature of my invention will be readily clear, as will

also the fact that various modifications may be made within its scope. Having however thus described one form which my invention may take, what I claim as new and desire 5 to secure by Letters Patent is:

A bed having in combination a wooden bed post having a flat face and a slot opening upon said face, a pin on said post extending transversely through the slot, a 10 metal side rail having secured to its vertical leg at one end a vertically extending L-shaped plate of substantial length, so as to extend both above and below the rail, said plate being provided with a slot and adapt- 15 ed to fit against the flat face of the bed post, over the slot therein, and a part secured to

said vertical leg of the rail and protruding through the slot in said plate, said part being adapted to enter the slot in the bed post and engage the pin, the portion of said part 20 that extends through the slot in the plate being of a size and shape in cross section corresponding in size and shape to the slot of the plate to completely close the said slot, 25 said rail, plate and part being secured together by rivets passing through the vertical leg of the side rail.

In witness whereof, I hereunto subscribe my name this 23rd day of January, A. D. 1919.

MORRIS B. OKUN.
